GARMENT SLEEVE IRONER

John H. Leef and George H. Leef, Minneapolis,
Minn.

Application April 20, 1936, Serial No. 75,274

2 Claims. (Cl. 223—74)

Our invention provides an extremely simple and highly efficient device herein designated as "Garment sleeve ironer" and is in the nature of an improvement upon the structures disclosed in our prior patents Nos. 1,937,656 of December 5, 1933, entitled "Garment leg ironer", and 2,022,210 of November 26, 1935, entitled "Garment sleeve ironer".

Although this application is entitled Sleeve ironer, the structure disclosed herein can readily be used for pressing or ironing legs or other tubular portions of garments having bulged portions at one end thereof. Obviously, the size of the ironer may be varied to meet any desired 15 size or condition.

Sleeves of many garments, such as those of shirts, have a straight taper to them and are not known as "form-fitting" garments. In the pressing of such garments a plain tapered ironer 20 will press out the wrinkles sufficiently well. However, in the pressing of wash suits and jackets and other form-fitting garments such a plain tapered ironer is entirely inadequate. In garments of this nature that part of the 25 sleeve on the outside immediately below the shoulder is puffed or bulged outwardly to give ample room for the enlarged muscular part of the arm and shoulder. When one attempts to press one of these form-fitting sleeves on a 30 straight tapered sleeve ironer that enlarged portion around the shoulder is not filled out. Consequently, longitudinal creases and wrinkles are formed in this bulged portion. In the process of drying these wrinkles and creases are ironed 35 into the garment and a separate operation is required to iron them out again. As such an operation takes time, it obviously increases the cost of pressing.

The object of our invention is to obviate this 40 extra step and to create a sleeve ironer which will press the sleeve and the bulged shoulder portion thereof at the same time.

A further object of our invention is to provide 45 a garment sleeve ironer capable of pressing sleeves having great variance, both as to length and width.

Referring to the drawing, wherein like characters indicate like parts throughout the several 50 views,

Fig. 1 is a side elevation of an assembly of the improved sleeve ironer;

Fig. 2 is an edge elevation showing the left-hand member of Fig. 1 turned toward the left, 55 some parts being broken away; and

Fig. 3 is an edge elevation of the right-hand member shown in Fig. 1 turned toward the right, some parts being broken away.

A fixed boot 4 is secured to base 5 by means of studs or the like 6. The movable boot 7, as shown, is attached to lower portion of fixed boot 4 by means of a spring link 8. Said spring 8 is loosely bent around the inset stud 9 in the central portion of movable boot 7 at its upper end, and is adapted to fit into a slot 10 in the lower portion of the fixed boot 4. Thus it will be seen that movable boot 7 is mounted for rocking action with respect to the fixed boot 4 and further is under strain to move away from the fixed boot 4.

Each boot is provided at its corresponding lower outside portion with an outwardly spring-pressed supplemental wing or plate 11, pivoted at its upper portion to its respective boot at 12. Each boot is provided with a pocket 13 and each supplemental wing or plate with a pocket 14. Into these pockets springs 15 are adapted to be set. It will be observed that the wings 11, being mounted with their inside edges flush with the inside edges of the respective boot to which each 20 is attached, and further being pivoted to their respective boots at the same height, that they are adapted to co-operate to give the effect of a single supplemental wing. Each of said boots is 25 hollow, as illustrated at 16, to permit the introduction and emission of steam by connections 30 not here deemed to be necessary.

It is important to note the following: Movable boot 7 is mounted for rocking action in respect to fixed boot 4; the movable boot 7 being connected as it is to the fixed boot 4 by leaf spring or link 8, is under constant strain to move away from the fixed boot; the lower portion of the supplemental wings or plates 11 are under constant pressure to move outward due to the action 35 of springs 15, the supplemental wings are so mounted with respect to one another, and further with respect to the boots, that they are adapted to co-operate so as to give the effect of a single 40 wing.

Note that the two wings 11 are substantially in a common plane and their adjacent edges are adapted to be brought substantially into contact when the two boots are moved closely together.

The ironer illustrated in the drawing is one 50 adapted for pressing of the right sleeves of garments. To press a left sleeve of a garment, it is necessary to have an ironer with outwardly spring-pressed wings 11 on the opposite side of the boots.

The operation of the improved boot is as follows:

The proper sleeve is pulled large end first over the two boots until the enlarged upper portion 5 of the arm is filled out by the outwardly spring-pressed supplemental wings 11.

It is to be noted that the boots are shaped to conform generally with the curved arm portion of a garment, and as they are under spring 10 tension to move apart, and capable of rocking action, the arm portion being pressed will be completely expanded and pressed without putting any undue tension on any part thereof.

From the above, it will be obvious that our invention 15 is capable of modifications and variations within the scope of the invention herein disclosed and claimed.

What we claim is:

1. In a device of the kind described, the combination with upright boots one of which is movable toward and from the other, of co-operating outwardly spring-pressed wings pivotally connected one to the lower portion of each of said boots, said wings being disposed substantially in the same plane with their adjacent edges extended approximately to the adjacent inner side edges of said boots and adapted to be brought 10 closely together when said boots are moved closely together.

2. The structure defined in claim 1 in which said wings are of substantially flat formation and are pivoted to the legs at their upper ends. 15
